UNITED STATES PATENT OFFICE.

HENRY W. MORGAN, OF ROCHESTER, NEW YORK.

NAILING-MACHINE.

1,091,691.

Specification of Letters Patent. Patented Mar. 31, 1914.

Application filed August 15. 1911. Serial No. 644,207.

To all whom it may concern:

Be it known that I, HENRY W. MORGAN, of Rochester, in the county of Monroe and State of New York, have invented certain new and useful Improvements in Nailing-Machines; and I do hereby declare the following to be a full, clear, and exact description of the same, reference being had to the accompanying drawings, forming a part of this specification, and to the reference-numerals marked thereon.

The present invention relates to nailing machines and it has for its object to provide improved mechanism of this nature more particularly adapted for driving a plurality of nails simultaneously into the several sides of an object, the machine of the present embodiment being designed particularly for nailing in the heads of kegs.

The improvements are further directed toward simplicity and toward promoting convenience and speed in operation.

To these and other ends the invention consists in certain improvements and combinations of parts all as will be hereinafter more fully described, the novel features being pointed out in the claims at the end of the specification.

In the drawings: Figure 1 is a perspective view of a keg nailing machine constructed in accordance with and illustrating one embodiment of my invention taken from a point to the right and in front of the machine; Fig. 2 is a perspective view taken from the right in rear of the machine; Fig. 3 is a top plan view of the carrying frame for the nailing units showing the driving mechanism, the same being taken in horizontal section through the supporting frame substantially on the line 3—3 of Fig. 1; Fig. 4 is a detail section taken substantially on the line 4—4 of Fig. 3 to show more particularly the manner of operating the nail drivers; Fig. 5 is a side elevation of one of the nail chucks; Fig. 6 is a top plan view thereof; Fig. 7 is a section taken substantially on the line 7—7 of Fig. 6, and Fig. 8 is an end elevation of one of the nail chucks.

Similar reference numerals throughout the several figures indicate the same parts.

To first give an idea of the general arrangements of the machine it may be said that in the present embodiment the keg or work piece is designed to remain stationary beneath a vertically sliding mechanism that

is brought down upon it to position a plurality of nailing units circularly about the same, while after the nailing operation the mechanism is raised to release the work piece which is removed and replaced by another. 60

Referring more particularly to the drawings, 1 indicates a substantially vertical main supporting frame at the base of which is arranged the work support 2. The latter may be of any suitable nature, being in the present instance shown to comprise a truck traveling on tracks 3 and forming part of a conveyer by means of which the kegs are delivered to and removed from the machine, but it will be later understood that a simple 70 platform or, for that matter, the floor upon which the machine rests, might be utilized in this capacity.

Slidable vertically up and down above the work support on guides 4 on the frame 1 is 75 a preferably annular carrying frame 5 upon the upper side of which are mounted a plurality of nailing units embodying chucks 6 that are arranged radially to drive the nails toward a common center. The chucks are 80 each independently adjustable toward and from the center of the annular carrying frame in guides 7 being secured in adjusted position in any suitable manner, as by bolts 8 operating in slots 9 in the frame, the latter being indicated in dotted lines in Fig. 4. The inner ends of the chucks are each preferably provided with depending fingers 10 that, in the present instance, project downwardly within the central opening of the 85 annular frame 5 and have inclined faces 11, the purpose of which is to center the keg or work piece properly with respect to the chucks as the latter are lowered upon it, as will be understood from an inspection of 90 Fig. 5.

Each chuck comprises a lower portion 6 and an upper portion 12, the adjacent faces of which are suitably recessed to conjointly form the nail channel 13 and the channel 100 for the driver 14. The latter is provided with a cross head 15 at its outer end that travels in a way 16 in the lower member 6 and is held in place by a cover plate 17 at the top, while at the inner end of the nail channel a sufficient recess is provided for the accommodation of the lower yielding chuck jaw 18 which is pivoted at 19 to the member 6 and pressed upwardly by a spring 20 arranged in a pocket 21 in the latter. 110

The opposing yielding jaw 22 is yoke-shaped so that the upper removable block 12 of the chuck may be accommodated between its arms 23, which are pivoted at 24 to the member 6, while the said block is undercut at 25 to accommodate the end of the jaw beneath it, this portion of the block 12 being also provided with a pocket 26 containing a spring 27 which bears against the said jaw 22.

10 The upper block 12 is itself held in place for relative movement toward and from the lower portion of the chuck by pins 28 on the latter fitting recesses therein and by a yoke-shaped clip 29 that straddles the block 12 and has the lower hooked ends 30 of its arms detachably engaging pins or projections 31 on the portion 6. This clip holds the block 12 yieldingly in place by the engagement there- 15 with of a spring 32 arranged in a pocket 33 in the block so that the latter may accommodate itself readily to irregularities in the passage of the nail through the nail channel, and it will also be seen that the block is re- 20 movable by simply detaching the clip 29 so that access may be had to the nail channel when necessary. The feed channel 34 that delivers the nails to the nail channel 13 is formed in the upper block 12 of the chuck, 25 the nails entering at its mouth 35 from the nail feed, as will be hereinafter described.

The drivers 14 of all the nailing units are simultaneously operated by a rock shaft 36 that is journaled at 37 in a bridge piece 38 30 spanning the annular carrying frame 5 in a manner to support the latter so that the frame is virtually hung upon this shaft. Secured to the lower end of the shaft as it projects through the bearing 37 is a member 39 35 having upper and lower laterally projecting flanges 40 and 41 that are spaced longitudinally of the shaft and to these flanges alternately are pivoted at 42 the respective ends of connecting rods 43, the opposite ends of 40 which have hooked portions 44 that enter at the sides of the ways 16 of the chucks and coöperate with the cross heads 15 of the drivers, the outer ends of the latter being provided with pins 45 with which the 45 hooked portions engage to withdraw the drivers, while a ball 46 is preferably interposed between the hooked portion 44 of each rod and the main portion of the cross head that receives the driving pressure to reduce 50 friction. It will thus be seen that as the shaft 36 is rocked the connecting rods will travel in and out and operate the drivers, and the purpose of pivoting these connecting rods alternately to the flanges 40 and 41 55 is to allow them to clear each other and not interfere when an extreme stroke is made. It is not thought necessary to further describe the manner of driving the nail.

60 The upper portion of the shaft 36 is slid- 65 ably journaled at 47 in a forwardly extend-

ing bracket 48 on the supporting frame 1 and a counter-weight 49 is connected by a chain 50 passing over pulleys 51 and 52 to the end of the shaft so that the shaft and the frame 5, that it carries, may be raised and lowered with little effort on the guides 4, and for the purpose of thus manipulating it a downwardly projecting rack bar 53 is provided on the bracket 48, with which meshes a pinion 54 on a shaft 55 journaled in the bridge piece 38 of the same and provided with a wheel or handle 56 that the operator may manipulate from the front of the machine, as the work pieces are put in place on the work support 2.

70 The function of the projections 10 on the several chucks for centering the latter over the keg or work piece as the frame 5 is lowered, has been before described, but in order to first properly approximate the position of 75 the work piece on the support, adjustable stops or abutments are provided on the frame 1 having the present form of laterally projecting screw-bolts 57 that are held in adjusted position by lock-nuts 58. The kegs 80 are thrust against these when inserted and in order to halt the downward movement of the frame 5 carrying the nailing units so that the latter will deliver at the proper point, as at the chime A of the keg B having 85 the head C, (Fig. 5) adjustable stops 59 are threaded into brackets 60 on the bridge piece 90 38 of the frame that engage the top or head of the work piece as the frame is lowered.

95 The shaft 36 is driven by a shaft 61 journaled in brackets 62 and 63 on the main frame, which shaft 61 is itself driven through gearing 64 and 65 from a shaft 66 that is in turn driven by gearing 67 and 68 100 from the main driving shaft 69 having a belt pulley 70 thereon. A suitable clutch mechanism (not shown), controlled by a hand lever 71 accessible at the front of the machine, throws the gearing 64—65 between the shaft 66 and the shaft 61 in or out of 105 operation at the will of the operator by disconnecting the gear 67 from shaft 66 or the reverse, so that the shaft 61, and with it the nail driving mechanism is operated intermittently, as desired, from the continuously turning main driving shaft only when the driving units are in proper coöperation with the work piece.

110 The connections between the shaft 61 and the rock shaft 36 for operating the latter, comprise a crank 72 on the upper end of the shaft 61 to which is attached a connecting rod 73. The other end of this connecting rod is pivoted at 74 to a crank 75 on a sleeve 76 that surrounds the shaft 36 within the bearing 47 on the bracket 48 and turns freely in the bearing while being locked against rotation on the shaft 36 in any suitable manner, as by the key 77 that permits the shaft 36 to slide longitudinally 115 120 125 130

within the sleeve and bearing. The crank 72 is shorter than the crank 75 so that as the former revolves with the shaft 61 the latter only oscillates and rocks the shaft 36 5 to operate the connecting rods 43 and actuate the drivers 14, as before described.

When the chucks 6 of the nailing unit are adjusted inwardly or outwardly on their guide 7 to accommodate the machine to kegs 10 or work pieces of different sizes, the limit of the throw of the drivers 14 must, of course, be correspondingly changed, and to effect this I provide the connecting rod 73 between the shafts 61 and 36 with threaded 15 portions 78 by means of which it may be lengthened or shortened and the crank 75 thus be made to move through an arc of greater or less degree upon the rotation of the crank 72.

20 The nails are fed to the mouths 35 of the feed passages 34 in the upper blocks 12 of the various nailing units, through lower feed tube sections 79 carried with the frame 5 that telescope upon upper sections 80 leading from the usual, or any preferred form, 25 of nail hoppers 81 so that the upward and downward movement of the frame 5 does not interfere with the nail feed.

As to the other necessary accessories of 30 the nailing machine, these have been shown generally in the drawings, but it is not thought that they require any detailed description as they form no part of the present invention.

35 I claim as my invention:

1. In a keg nailing machine, the combination with a work support, of an annular carrying frame, a centrally arranged supporting member therefor, a plurality of 40 radially arranged and circumferentially spaced nailing units on the said frame, means for operating the frame in the direction of its axis toward and from an article on the work support, whereby the nailing 45 units may be caused to surround the keg, and means for operating all of the nailing units simultaneously.

2. In a nailing machine, the combination with a work support, of a carrying frame, 50 a plurality of radially arranged nailing units thereon, means for operating the frame toward and from the work support and an adjustable stop on the frame adapted to engage a work piece on the support 55 and to position the nailing units with reference thereto.

3. In a keg nailing machine, the combination with a work support, of an annular carrying frame, a centrally arranged supporting member from which said frame is 60 suspended, a plurality of radially arranged and circumferentially spaced nailing units on the frame, means for operating the latter and its supporting member toward and 65 from an article on the work support to

cause the nailing units to surround the article, and means for operating all of the nailing units simultaneously.

4. In a nailing machine, the combination with a work support, a supporting frame at 70 one side thereof, a carrying frame mounted for sliding adjustment on the supporting frame, a plurality of radially arranged nailing units on the carrying frame movable with the latter to surround an article 75 on the work support and an adjustable stop on the supporting frame arranged to center the article on the work support with respect to the carrying frame.

5. In a nailing machine, the combination with a reciprocable carrying frame, and a supporting member therefor movable relatively thereto, of a plurality of radially arranged nailing units on the frame adapted to surround a work piece toward which the 80 frame is moved and operating devices for the nailing units actuated by the relative movement of the frame and its supporting member.

6. In a nailing machine, the combination with a slidable carrying frame, of a plurality of radially arranged nailing units mounted thereon, drivers therefor, a bearing and a shaft for operating the drivers arranged centrally with respect to the group 95 of nailing units and slidably axially in the bearing in the direction of sliding movement of the carrying frame.

7. In a nailing machine, the combination with a support and a carrying frame 100 slidably thereon, of a plurality of radially arranged nailing units mounted on the frame, drivers therefor, a bearing on the frame, a bearing on the support, both bearings being arranged centrally of the group of nailing 105 units and a shaft for operating the drivers journaled in both bearings and slidably mounted in the bearing on the support.

8. In a nailing machine, the combination with a reciprocable carrying frame and a 110 plurality of radially arranged nailing units thereon, of a supporting member for the carrying frame movable relatively thereto and arranged centrally of the group of nailing units and means for operating the nailing 115 units actuated by the relative movement of the supporting member and carrying frame.

9. In a nailing machine, the combination with a support and a carrying frame 120 slidably thereon and provided with a bridge piece, of a plurality of nailing units mounted on the frame, drivers therefor, a bearing on the support, a shaft slidably mounted therein and journaled in the bridge piece 125 of the frame to project therethrough and operating connections between such projecting portion of the shaft and the drivers and arranged between the bridge piece and the frame.

10. In a nailing machine, the combination with a support and a carrying frame slideable thereon, of a plurality of nailing units mounted on the frame, drivers therefor, a bearing on the support, a shaft for operating the drivers slideable in the bearing, a crank having a slideable relation to the shaft but rotatable therewith, a connecting rod attached to the crank and means for operating the connecting rod.

11. In a nailing machine, the combination with a support and a carrying frame slideable thereon, of a plurality of nailing units mounted on the frame, drivers therefor, a bearing on the support, a sleeve rotatable in the bearing and having a crank arm, a shaft for operating the drivers slideable in the sleeve but locked for rotation therewith, a connecting rod attached to the crank and means for operating the connecting rod.

12. In a nailing machine, the combination with a carrying frame and a plurality of nailing units thereon, of a supporting member for the carrying frame arranged centrally of the group of nailing units and arranged to rotate relatively to the frame, and means for operating the nailing units actuated by the rotation of the supporting member with respect to the frame.

13. In a nailing machine, the combination with a plurality of radially arranged nailing units, drivers therefor, connecting rods for operating the drivers and a shaft arranged centrally with respect to the group of nailing units and having the connecting rods pivoted eccentrically thereto at one end.

14. In a nailing machine, the combination with a plurality of radially arranged nailing units, drivers therefor, connecting rods for operating the drivers, a rock shaft arranged centrally with respect to the group of nailing units and having the connecting rods pivoted eccentrically thereto at one end, and adjustable means for rocking the shaft to a greater or less degree to vary the stroke of the drivers.

15. In a nailing machine, the combination with a plurality of radially arranged nailing units, drivers therefor, connecting rods for operating the drivers, a rock shaft arranged centrally with respect to the group of nailing units and having the connecting rods pivoted eccentrically thereto at one end, a crank on the rock shaft, a driving shaft, a crank on the latter, a connecting rod at-

tached to both cranks and means for varying the length of such connecting rod to vary the stroke of the drivers.

16. In a nailing machine, the combination with a plurality of radially arranged nailing units, drivers therefor, connecting rods for operating the drivers, a shaft arranged centrally with respect to the group of nailing units and lateral projections carried by the shaft and spaced longitudinally thereof and to which the ends of adjacent connecting rods are respectively pivoted for the purposes described.

17. In a nailing machine, the combination with a carrying frame, of a plurality of radially arranged nailing units mounted thereon each embodying a chuck, and an extension on each of a plurality of the chucks having an inclined inner face adapted to center a work piece as it enters between the nailing units, the said faces jointly constituting a substantially conical guide for the work piece.

18. In a nailing machine, the combination with an annular carrying frame, of a plurality of radially arranged nailing units mounted thereon, each nailing unit embodying a chuck, and an extension on each of a plurality of the chucks arranged to project into the opening of the annular frame and having an inclined inner face adapted to center a work piece as it enters between the nailing units, the said faces jointly constituting a substantially conical guide for the work piece.

19. In a nailing machine, the combination with a chuck embodying two relatively movable members conjointly forming the nail passage, one member being provided with projections, of a yoke straddling the other member and having its ends hooked over the projections and a spring interposed between the yoke and the last mentioned member.

20. In a nailing machine, the combination with a chuck embodying two relatively movable members conjointly forming the nail passage, of a pair of yielding jaws pivoted to one of the members, one of said jaws being yoke-shaped to embrace the other member.

HENRY W. MORGAN.
